H. E. VAN NESS

ENGINE STARTER

Filed June 28, 1918

INVENTOR.

Henry E. Van Ness
BY Rector, Kibben, Davis & Macaulay
New York ATTORNEYS.

UNITED STATES PATENT OFFICE.

HENRY E. VAN NESS, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed June 28, 1918. Serial No. 242,347.

To all whom it may concern:

Be it known that I, HENRY E. VAN NESS, a citizen of the United States, residing at Elmira, in the county of Chemung and 5 State of New York, have invented certain new and useful Improvements in Engine Starters, of which the following is a specification.

My invention relates to a starter for engines, more particularly internal combustion engines, and pertains to the drive or transmission portion thereof between the starting motor and the part, such as the fly wheel, of the engine to be started.

15 The object of my invention is to provide in such a drive or transmission a means for transmitting the power therethrough initially with a yielding pressure and finally with a rigid or positive pressure. In drives 20 of the class and character to which my invention is particularly applicable a yielding driving connection in the form of a coiled spring is provided to transmit the power yieldingly and also to store up energy until the fly wheel is broken loose 25 and started. Such a spring has its limits and in order to prevent any overtaxing of the spring and to provide a positive or rigid drive when the tension limit of the 30 spring is reached and to thereby prevent setting of the spring, my present invention is employed.

Speaking in general terms and referring 35 to the particular embodiment employed, my invention consists in providing means whereby the power will be transmitted to the rotatable member or screw shaft yieldingly through the spring until the spring has received a predetermined amount of angular deflection whereupon a rigid or positive 40 driving connection will be called into play at a predetermined point below the elastic limit of the spring, thereby relieving the spring from the further and greater degree 45 of power transmission but without interfering with the flexibility of said spring within safe limits.

In the drawing Fig. 1 is an elevation partly in section of a drive embodying my invention. Figs. 2, 3 and 4 are cross sections on lines indicated by corresponding figures and looking in the direction of the arrows, and Fig. 5 a plan view of a portion of the drive shown in Fig. 1.

55 For convenience in illustration and de-

scription of my invention I have shown a specific embodiment thereof in the type of drive known as the Eclipse-Bendix drive, but it will be understood that my invention is not to be limited to this particular type 60 but may be embodied in types of other construction.

Referring to the particular embodiment shown the power motor, such as an electric starting motor, is indicated diagrammatically at A. In the construction being described, which is of the single reduction type, the armature shaft is extended to form a driving shaft 1 on which the drive or transmission is supported and by which it 65 is driven. To the outer end of this shaft there is secured by means of the pin 2 a driving head in the form of a collar 3 (through which said stud passes and thence into the driving shaft) and a cylindrical 70 inwardly projecting extension 4. The screw shaft 5 is here in the form of a sleeve or hollow shaft fitting upon the driving shaft 1 and is operatively connected with the driving head 3 through the coiled driving spring 6, one end of which is anchored to the pin 2 and the other to a stud 7 which screws into the driven head portion of the screw shaft. As shown such portion is 75 integral with the screw shaft, but this is not 80 essential as it may be made separate and detachable and secured thereto.

Upon the screw shaft is mounted the driving member which is in the form of a pinion 8 screwthreaded on said shaft and adapted 85 to mesh with the teeth 9^a of the fly wheel 9 of the engine, according to the particular installation illustrated.

The description so far given is applicable 90 to said Eclipse-Bendix drive and the differences thereover, now to be described, particularly concern my present invention. The extension 4 is provided with one or more, preferably two, projections or tongues 10 which are adapted to be received by and to 100 operate within the slots 11 formed by and between the projections or tongues 12 extending outwardly from the outer end of the screw shaft or its driven head 5^a. As shown in Figs. 2 and 3 the slots 11 are of a length 105 to permit of a partial rotation of the tongues 10 before they come into contact with the tongues 12 and thereupon and thereafter constitute a rigid or positive driving connection 110 and transmit the power instead of the spring.

Thus initially the power is transmitted from the driving head 3 through the spring 6 and after a predetermined amount of angular deflection of such spring which is thereby cushioned, the tongues 10 and 12 are brought into contact and the further power is transmitted directly through these driving heads and not through the spring. The screw shaft is thereby rotated or driven initially with a 10 yielding pressure through the coiled spring and finally by a positive pressure directly through said driving heads. In this manner and by these means the driving spring is enabled to perform all of its intended functions and is relieved against any breakage 15 or damage that would result in case of too great angular deflection which would cause a permanent set in the spring.

This construction also takes care of the 20 rebound of the spring (which has a tendency to expand the spring and cause breakage) inasmuch as excessive expansion is prevented by the contact of the members 10 and 12, moving relatively in directions the opposite 25 to that when acting to relieve the spring of excessive torsion strain. Thus this means limits the relative movements of the driving and driven elements in both directions.

Although I have described my invention in 30 connection with a drive of the so-called single reduction type, in which the driving

shaft is substantially the armature shaft extended, it will be understood that it is equally applicable to the double reduction type in which the starting motor is indirectly connected as by gearing with a driving shaft, both of which types of drives are exemplified in Bendix Patent No. 1,125,935.

The construction of the heads together with their tongues and slots is such that a 40 yielding longitudinal movement of the screwshaft is permitted in the event that the pinion teeth should abut the flywheel teeth end to end.

I claim:

A transmission or drive for engine starters including a driving and a driven element, and a spring operatively connecting them for initial driving, said elements having complementary tongues and slots permitting a 50 limited relative movement one with respect to the other and adapted to operatively engage each other for direct driving at the end of such limit, the said tongues and slots being so constructed and arranged as to permit the driven element to move longitudinally in either direction with respect to the driving element and said tongues being normally positioned in contact with one 55 side of their slots.

HENRY E. VAN NESS.
